F. E. KRAUSS

PORTABLE FIRE EXTINGUISHER

Filed Sept. 15, 1923

*inventor
Friedrich Emil Krauss
By Knight Bros*

UNITED STATES PATENT OFFICE.

FRIEDRICH EMIL KRAUSS, OF SCHWARZENBERG, SACHSEN, GERMANY.

PORTABLE FIRE EXTINGUISHER.

Application filed September 15, 1923, Serial No. 662,899, and in Germany September 16, 1922.

This invention relates to a portable chemical fire extinguisher and more particularly to that type which is provided with an expansion chamber at the riser or ascending pipe in order to prevent the so-called "pushing" or overflowing of the apparatus. In apparatus of this kind as hitherto constructed the expansion chamber was arranged within the shell at the outside of the ascending pipe, an opening in the wall of the ascending pipe putting the interior of the ascending pipe and the chamber in communication. In this known construction certain difficulties arose in the manufacture of the chamber itself as well as in its combination with the ascending pipe. These drawbacks have been completely eliminated by the improved construction, and at the same time further technical advantages have been obtained. The invention consists essentially in disposing the expansion chamber at the mouth of the ascending pipe. The chamber is preferably made of plain cylindrical shape and is carried through the top of the shell and thus lends itself to the simple and substantial attachment of the ascending pipe, which need no longer be fixed at the inside of the upper portion of the shell, which is generally accessible with difficulty. The nozzle of the extinguisher is preferably arranged directly upon the expansion chamber.

An embodiment of my invention is illustrated in the drawing by way of example, the improved extinguisher being shown in longitudinal section.

Referring to the drawing *a* is the shell of the extinguisher, which may have any suitable shape, which contains a bottle of

acid *b* or any other device for producing gas under pressure when actuated by a striking-pin *c*. In the interior of the extinguisher the ascending pipe *d* is provided upon the upper end of which the expansion chamber *e* is mounted. Upon the latter is fixed the spraying nozzle *f*, for instance at the side, as shown. The chamber *e* is secured in the cover *g* of the extinguisher and may partly project beyond it.

In the example shown the chamber *e* is soldered into the cover *g* and upon it is attached one end of the handle *h*. The handle may obviously be differently disposed, for instance at the side, particularly if the shell is conical. Instead of soldering the expansion chamber *e* into the cover *g* of the extinguisher, it may be screwed into it, a suitable screw socket and stuffing box being provided, so that the chamber together with the ascending pipe may be withdrawn from the shell whenever desired. Other modifications within the ambit of the claims will easily suggest themselves.

What I claim as my invention and desire to secure by Letters Patent is:—

In a fire extinguisher, the combination of a shell, a cylindrical expansion chamber penetrating the top of said shell and fixed in it, a nozzle at the side of the outer portion of said expansion chamber, and an ascending pipe opening into the lower end of said expansion chamber and having a small diameter in relation to that of the expansion chamber and being of uniform diameter in all its length.

In testimony whereof I affix my signature.

FRIEDRICH EMIL KRAUSS.
